DEMOUNTABLE VALVE GUARD FOR
SAXOPHONES AND THE LIKE

Earl J. Gillespie, Elkhart, Ind., assignor to The
Martin Band Instrument Company, Elkhart,
Ind., a corporation of Indiana

Application February 23, 1945, Serial No. 579,323

5 Claims. (Cl. 34—385)

1

This invention relates, in general, to musical instruments, and has particular relation to an improved demountable valve guard for saxophones and the like.

It is known that wood wind instruments are musical instruments in which the length of a pulsating column of air and the number of segments in which the pulsating column is divided may be altered by opening lateral ports controlled by valves or pads operated from the key mechanism of the instrument, for example, through suitable valve arms.

Guards have commonly been provided for guarding these valves or pads and the valve arms against injury which otherwise might occur. Unless properly guarded, the valves or pads, valve arms, or the hinges carrying same, or other parts, might be moved out of proper position or become distorted or bent, for example, by engagement with the clothing or other objects.

So far, the only removable guards that have been proposed have not been able to withstand normal use and handling of the instrument without becoming loose, with resulting wear in the guard attachment means, rattle, misalignment or interference with proper operation of the instrument. For example, in one previous form of attachment permitting removal and replacement of the guard, inwardly directed ends of the guard elements have been inserted in posts and set screws have been engaged in circumferential grooves in the inserted ends to hold the guard removably in place. This form of attachment permits the guard quickly to become loose under normal use and handling of the instrument, with the objectionable results set forth and other disadvantages. As a result, guards of the class described are usually fixedly secured in place against removal from the tubular body of the instrument. Where the guards are fixed against removal, the workman's difficulties in finishing the instrument are increased, and access to the valves or pads, valve arms, or the hinges carrying same or other parts, for example, for adjustment, cleaning or the like, is difficult.

One of the main objects of the present invention is to provide an improved form of demountable valve guard and attachment therefor of the class described which will not have the objectionable results set forth and other disadvantages encountered with the previously proposed demountable guards.

Another object of the invention is to provide an improved form of demountable valve guard and attachment therefor of the class described with

2

which the guard may be securely and firmly locked in place against becoming loose and against rattle, misalignment, or interference with proper operation of the instrument; also an improved demountable valve guard and attachment therefor which will permit ready removal and replacement of the guard.

Another object of the invention is to provide a demountable valve guard of the class described and attachment therefor having various features of novelty and advantages, and further characterized by its simplicity in construction, its effectiveness in use, its pleasing appearance, and its ease and economy in manufacture and assembly.

Another and more specific object of the invention is to provide a demountable valve guard of the class described and attachment therefor comprising internally threaded posts secured to the tubular body of the instrument, a demountable guard for the valve means, attachment parts fixed to the guard and having openings to fit demountably over the posts, shoulders on the attachment members, and screws having shanks adapted to be inserted into the openings in the attachment parts and screwed into the posts, the screws being provided with heads adapted, when the screws are screwed into the posts, to engage the shoulders firmly and securely and, at the same time, demountably to secure the guard in place on the tubular body.

Another more specific object of the invention is to provide in a device of the character set forth shoulders located within the openings in the attachment parts and spaced inwardly from the outer sides of these parts so that the heads of the attachment screws, when engaged with the shoulders, will enter and be positioned within the outer ends of the openings in the attachment parts.

Further objects and advantages of the invention will appear from the following detailed description, taken in connection with the accompanying drawing which illustrates the manner of constructing and operating one form of demountable valve guard and attachment embodying the present invention.

In the drawing:

Figure 1 is a fragmentary side elevational view of a saxophone having a demountable valve guard and attachment embodying the present invention;

Figure 2 is a fragmentary front elevational view of the saxophone, with demountable valve guard and attachment as shown in Figure 1; and

Figure 3 is a detail sectional view through one

of the demountable valve guard attachments and the adjacent portion of the wall of the tubular body of the instrument taken on the line 3—3 of Figure 1.

Referring now to the drawing, the invention is shown, for purposes of illustration, embodied in a saxophone which comprises a tubular body composed of the longitudinal tubular portion 1 which is preferably tapered, the bend 2, and the bell or flare 3, these three parts being firmly united, for example, by soldering or the like.

The bell 3 of the instrument has lateral ports controlled by valves or pads 4 and 5 which, for example, may be the B-flat and B-natural valves of the instrument, or other valves or pads. The valves 4 and 5 are carried by or mounted on arms 6 and 7, respectively, which are actuated, for example, through hinge sleeves or rods 8 and 9 from suitable key mechanism not shown.

The demountable valve guard 10 selected for illustration comprises an open framework composed of an inner guard element 10' of open and generally looped form, with a generally looped outer guard element 10'' united thereto at 10a, for example, by soldering or the like, and a guard element 10''' similarly united to the guard element 10'' at 10b. The guard thus formed is of pleasing appearance, and extends beyond the valves 4 and 5 and over the arms 6 and 7 and the hinges carrying same, effectively to protect these parts against injury.

Four short posts 12 extend outwardly from plates which are soldered or otherwise fixed to the tubular body of the instrument. In the illustrated embodiment of the invention, one of these posts 12 is shown fixed to the tubular portion 1, another to the bend 2, and two posts 12 are fixed to the bell 3, but this may, of course, vary. Each post 12 has a shoulder 13 at the inner end of its outer surface, and each post is internally threaded at 14.

At one end the guard element 10' has an attachment part 15 of generally knob-like form fixed thereto, and at the opposite end of the guard the guard element 10''' has a similar attachment part 15 fixed thereto. The out-turned ends of the inwardly directed portions of the guard element 10'' have similar generally knob-like attachment parts 15, 15 fixed thereto. The knob-like attachment parts 15 may be formed integral with the respective guard elements, or firmly joined or secured thereto by soldering or the like.

As shown in detail in Figure 3, each attachment part 15 has an opening 16 which fits demountably and preferably tightly over its attachment post 12. Each attachment part 15 also has a shoulder 17 thereon. These shoulders 17 are preferably located within the openings 16 and spaced inwardly from the outer sides or outer ends of the respective attachment parts. Screws 18 have shanks which are adapted to be inserted into the openings 16 and screwed into the posts 12. These screws 18 are provided with heads 19 adapted, when the screws are screwed into their respective posts 12, to engage the internal shoulders 17 firmly and securely and at the same time demountably to secure the guard in place on the tubular body of the instrument.

When the guard 10 is thus secured in place, the knob-like attachment parts 15 are clamped tightly between the shoulders 13 and the heads 19 of screws 18. The guard 10 is thus securely and firmly locked in place against becoming loose and against rattle, misalignment or interference with the proper operation of the instrument. The 75

guard elements forming the guard preferably have resilience or springiness which permits the attachment parts 15 to be sprung into place over the posts 12 further to eliminate any possibility that the attachments will become loose or that they will rattle in the use and handling of the instrument.

At the same time, the tubular body of the instrument may be finished before the guard 10 is applied, and the guard may then be quickly and conveniently secured in place. And it may be readily removed for adjustments, cleaning or the like, and readily replaced. When in place, any resilience or springiness in the guard elements 15 operates against the sides of the fixed posts 12 and not against or along the clamped or engagement contact of the parts which would tend to loosen the attachment and produce rattling and other objectionable results.

20 The embodiment of the invention shown in the drawing is for illustrative purposes only, and it is to be expressly understood that said drawing and the accompanying specification are not to be construed as a definition of the limits or scope of the invention, reference being had to the appended claims for that purpose.

I claim:

1. In an instrument of the class described having a tubular body and valve means therefor, the combination with said instrument of a mounting member having a base fixed to the body of the instrument, an integral internally threaded post extending from said base, an abutment shoulder on said base at the inner end of said post, a guard for said valve means, an attachment member of protuberant form fixed to said guard and having an opening extending therethrough and of a diameter for a distance greater than the length of said post to fit telescopically over said post, a shoulder at the inner end of said attachment member adapted to seat against the abutment shoulder on the base of said mounting member, the outer end of the opening which extends through said attachment member being countersunk to form a shoulder at the outer end of the post fitting diameter of said opening and outwardly of the outer end of said post, and a screw having a head and a shank adapted to be screwed into said post to position 50 with said head positioned within the countersunk outer end of the opening in said attachment member and seating against the shoulder in said opening to clamp the attachment member between the head of the screw and the abutment shoulder on said base.

2. In an instrument of the class described, a guard mounting according to claim 1 wherein the guard has springiness which operates against the side of the post and not against the threaded engagement between the screw and the post when the guard is in place.

3. In an instrument of the class described having a tubular body and valve means therefor, the combination with said instrument of a plurality of mounting members each having a base fixed to the body of the instrument, an integral internally threaded post extending from each base, an abutment shoulder on each base at the inner end of the adjacent post, a guard for said valve means, a plurality of attachment members of protuberant form fixed to said guard and each having an opening extending therethrough and of a diameter for a distance greater than the length of the adjacent post to fit telescopically over said post, a shoulder at the inner end of

each attachment member adapted to seat against the abutment shoulders on the bases of said mounting members, the outer ends of the openings which extend through said attachment members being countersunk to form shoulders at the outer ends of the post fitting diameters of said openings and outwardly of the outer ends of said posts, and screws having heads and shanks adapted to be screwed into said posts to positions with said heads positioned within the countersunk outer ends of the openings in said attachment members and seating against the shoulders in said openings to clamp the attachment members between the heads of the screws and the abutment shoulders on the bases of said mounting members.

4. In an instrument of the class described, a guard mounting according to claim 3 wherein the guard has springiness which operates against the sides of the posts and not against the threaded engagement between the screws and said posts when the guard is in place.

5. In an instrument of the class described having a tubular body and valve means therefor, the combination with said instrument of a mounting member having a base fixed to the body of the instrument, an integral internally threaded post fixed to said base, a guard for

10 said valve means, said guard having springiness therein, an attachment member fixed to said guard and having an opening extending therethrough and of a diameter for a distance greater than the length of said post to fit telescopically over said post whereby the springiness of the guard operates against the side of the post, and a screw having a head and a shank adapted to be screwed into said post and seating against said attachment member outwardly of the outer end of the post to clamp the attachment member between the head of the screw and the base of said mounting member without operation of the springiness of the guard against said screw connection.

15 EARL J. GILLESPIE.
